(57) **CLAIM**

The ornamental design for a fade haircut guide, as shown and described.

DESCRIPTION

FIG. 1 is a front elevational view of the fade haircut guide showing my new design, the rear elevational view being a mirror image thereof;

FIG. 2 is a left side elevational view, the right side elevational view being a mirror image thereof;

FIG. 3 is a top plan view thereof;

FIG. 4 is a bottom plan view thereof;

FIG. 5 is a top, front perspective view showing the fade haircut guide in a state of use; and,

FIG. 6 is a right side perspective view of the fade haircut guide shown in a state of use.

The broken lines illustrate the environment of the fade haircut guide and form no part of the claimed design.
